DESIGN FOR A HANDBAG OR THE LIKE

Adolph Schenker, New York, N. Y.

Application January 27, 1940, Serial No. 89,785

Term of patent 3½ years

To all whom it may concern:

Be it known that I, Adolph Schenker, a citizen of the United States, residing at New York, New York, have invented a new, original, and ornamental Design for Handbags or the like, of which the following is a specification, reference being had to the accompanying drawing, forming a part thereof.

In the accompanying drawing, Figure 1 is a side elevation of a handbag showing my new design, Fig. 2 is an end elevation of a handbag showing my new design.

The dominant feature of my design resides in the surface ornamentation appearing on the side of the handbag illustrated.

In the specific embodiment of the design illustrated the side of the handbag not shown is substantially like the side shown.

I claim as my invention:

The ornamental design for a handbag or the like, as shown and described.

ADOLPH SCHENKER.
